UNITED STATES PATENT OFFICE

DENNIS HOWARTH, OF CHESTER, PENNSYLVANIA.

DESIGN FOR TEXTILE FABRIC.

SPECIFICATION forming part of Design No. 30,929, dated May 30, 1899.

Application filed May 1, 1899. Serial No. 715,246. Term of patent 34 years.

To all whom it may concern:

Be it known that I, DENNIS HOWARTH, a citizen of the United States, residing at Chester, in the county of Delaware, State of Pennsylvania, have invented and produced a new and original Design for Textile Fabrics, of which the following is a specification, reference being had to the accompanying drawing, forming part thereof.

10 The drawing illustrates the embodiment of my design in a fabric.

As shown in the drawing, the leading or material feature of my design consists of a series of groups of parallel stripes of equal thickness throughout their entire length, each alternate group of stripes being wider than the other group—that is to say, the first group of stripes near the edge of the fabric is composed of a series of broad stripes parallel to each other and of equal thickness or

width throughout their entire length, whereas the next group is composed of a series of comparatively narrow or thin stripes parallel with each other and of equal thickness or width throughout their entire length. The next 25 group of stripes is similar to that first described. This order of arrangement is followed throughout the width of the fabric. The broad stripes are arranged in groups of three, while the narrow or thin stripes are arranged in groups of four.

Having described my invention, what I claim, and desire to secure by Letters Patent, is—

35 The design for textile fabric, as herein shown and described.

DENNIS HOWARTH.
